(57) **CLAIM**

The ornamental design for a field distribution box, as shown and described.

DESCRIPTION

FIG. 1 is a front perspective view of an example embodiment of a field distribution box showing my new design.

FIG. 2 is rear perspective view thereof.

FIG. 3 is a front view thereof.

FIG. 4 is a top view thereof.

FIG. 5 is a right side view thereof.

FIG. 6 is a left side view thereof; and,

FIG. 7 is a rear view thereof.

The field distribution box hereof may be used for controlling decentralized driving units, e.g., electric motors, and may supply electric power and/or control signals to the driving units.
